DESIGN FOR A PARKWAY SIGN

Harry F. Koelling, Park Ridge, Ill., assignor of one-half to Robert C. Feaster

Application February 21, 1938, Serial No. 75,307

Term of patent 7 years

To all whom it may concern:

Be it known that I, Harry F. Koelling, a citizen of the United States, residing at 914 W. Crescent Street, Park Ridge, in the county of Cook and State of Illinois, have invented a new, original, and ornamental Design for a Parkway Sign, of which the following is a specification, reference being had to the accompanying drawing, forming part thereof, in which

Fig. 1 is a front elevational view of a parkway sign showing my new design.

Fig. 2 is a side view of the parkway sign, and
Fig. 3 is a plan view of the same.

I claim:

The ornamental design for a parkway sign, as shown.

HARRY F. KOELLING.
